UNITED STATES PATENT OFFICE.

JOSEPH RAMSDEN MITCHELL AND FRANK XAVER FISCHER, OF OAKLAND, CALIFORNIA.

PORTABLE STEAM-BOILER.

SPECIFICATION forming part of Letters Patent No. 364,839, dated June 14, 1887.

Application filed November 27, 1886. Serial No. 220,094. (No model.)

To all whom it may concern:

Be it known that we, JOSEPH RAMSDEN MITCHELL and FRANK XAVER FISCHER, of Oakland, Alameda county, State of California, 5 have invented an Improvement in Portable Steam-Boilers; and we hereby declare the following to be a full, clear, and exact description of the same.

Our invention relates to an improved construction for portable steam-boilers, and it is based especially upon the patent issued to us December 19, 1882, No. 269,308. In that construction we have shown water-legs carried straight up, so that the outer walls meet the 15 boiler-shell in a line nearly or quite tangent to it, and this forms a sharp angular space within which it is difficult for water to circulate and where it would become filled with scale in a short time, and entirely impede the circulation 20 of the water.

In our present invention, which is especially applicable to portable steam-boilers for burning straw or other light material, although not limited to these, we have extended the water-legs above or up to nearly the water-line and in the arc of a circle the center of which coincides with the center of the boiler-shell, this arc extending longitudinally the whole length 25 of the water-legs.

30 Referring to the accompanying drawings for a more complete explanation of our invention, Figure 1 is a longitudinal vertical section. Fig. 2 is a transverse vertical section taken through the rear. Fig. 3 is a vertical section 35 taken through the front. Figs. 4 and 5 are views of the supplemental grate-section.

C is the ordinary multitubular boiler having the water-legs A A' extending the full length of the boiler along the sides from the line D 40 to D', as shown in Fig. 1. The outer sheets of the water-legs A A', which were in the original patent riveted flat to the shell and standing tangent thereto, are in the present case curved outward, so as to form an arc of a circle the curve of which corresponds to that of the boiler-shell, as shown at B B', and this distance is retained to a point at or about the level of the water-line within the boiler, at 45 which point the shell is curved inward until 50 it brings the upper flange in contact with the

boiler-shell to which it is riveted. The inner plates of the water-legs are carried up nearly vertical or at a slight inclination, and have a flange bent so as to fit against the lower part of the boiler-shell on each side, where they are 55 riveted, the shells being properly stayed by bolts in the usual manner, as shown in Fig. 3.

Passages or openings *i* are made between the shell of the boiler and the upper part of the water-legs, so that a free circulation may be 60 provided. By this construction the water-space is considerably enlarged, thus affording a free circulation for the water and steam, and also allowing a sufficient space for a reasonable amount of scale to form without any injurious results. We also provide complete 65 water-jacket sides for the combustion-chambers, dispensing with liners and avoiding all danger of overheating the sides of the combustion-chamber, which occurs through defective liners or from their being carelessly left out. This construction also facilitates the putting in and taking out of the tube-sheet, because by extending these side sheets upward in the arc of a circle sufficient space is left 70 within for the insertion of the rivets, which are put in through hand-holes P P' made in the outer sides of these curved water-legs, as shown in Fig. 2. It is thus easy to remove or replace 75 the tube-sheet whenever desired. Hand-holes 80 T T' are also made in the rear ends of the water-legs for the purpose of cleaning them, and these can be more easily put in on account of the curve of the outer walls of the water-legs, as before described. These holes are 85 covered by removable plates, as shown.

The dry-pipe *m* extends along the upper part of the boiler and connects through a short vertical pipe with the steam drum or dome *n*. The dry-pipe is supported by brackets at each 90 end, the forward one having a clamping-screw, *o*, which being loosened the pipe may be drawn out through the opening *P*.

The grate for straw-burning purposes consists of the longitudinal tubes *a*, the front ends 95 of which are capped and may be slightly lower than the rear ends to insure circulation. The rear ends are turned up and are connected with the bottom of a transverse drum, *b*. This drum extends across between the water-legs, 100

into which it opens at both ends, and it has the central pipe, *c*, which connects with the boiler, so that water therefrom circulates within the tubes *a* and through the drum *b*. 5 This drum also serves as a water-back bridge-wall, and, besides assisting in making steam, it is protected from the heat and prevented from burning out.

The tubes *a* are separated by considerable 10 spaces, and when wood, coal, or other similar fuel is to be employed it is necessary to insert grate-bars *d*, the spaces between which are much narrower. These bars have connecting 15 transverse bars *e*, the ends of which are curved to fit the sides of the tubular bars, upon which they rest, as shown in Fig. 5. They may thus be removed or replaced at any time with little trouble.

Having thus described our invention, what 20 we claim as new, and desire to secure by Letters Patent, is—

1. The transverse drum forming a bridge-wall at the rear of the furnace, and having its ends connected with the water-legs, and the 25 central portion with the lower part of the boiler, as shown, in combination with the tubular grate-bars having their rear ends connected with the drum and their front ends at a lower level and closed, substantially as herein 30 described.

2. The dry-pipe supported in brackets in the upper part of the boiler, the clamping bolt and nut by which the sides of the front bracket are compressed to hold the pipe, or loosened 35 to release it, and the opening made in the boiler-head in line with the pipe, substantially as herein described.

3. The water-legs extending downward upon each side of the boiler, and having a length 40 equal to or greater than it, said legs having

openings and plates *T* at the ends, and their upper parts corresponding to the curvature of the boiler, substantially as and for the purpose herein described.

4. The boiler having pendulous water-legs 45 extending downward upon each side, the upper part of the outer plates of said legs being curved so as to form an arc corresponding with the curvature of the boiler-shell, substantially as herein described. 50

5. The boiler having the water-legs extending downward upon each side, the outer plates of said legs having their upper edges riveted to the boiler-shell at or above the water-line within said boiler, and curved outwardly so as 55 to form an arc nearly or quite coincident with the curvature of the boiler-shell, whereby a space is left between the shell and the outer sheet, substantially as herein described.

6. The boiler having the downwardly-extending water-legs upon each side, the outer plates of the legs being curved to an arc nearly or quite corresponding with the curvature of the boiler-shell, and having the hand-holes or openings made in them coincident with the 65 tube-sheet, substantially as herein described.

7. The tubular grate-bars and transverse water-back bridge-wall, as shown, in combination with the intermediate supplemental grates with transverse bars having their ends 70 curved to fit the sides of the tubes and supported thereby, substantially as herein described.

In witness whereof we have hereunto set our hands.

JOSEPH RAMSDEN MITCHELL.
FRANK XAVER FISCHER.
